UNITED STATES PATENT OFFICE.

WALLACE ATHERTON McCURD, OF NORTH FINCHLEY, ENGLAND.

FLYING-MACHINE.

No. 924,813.

Specification of Letters Patent.

Patented June 15, 1909.

Application filed April 17, 1908. Serial No. 427,583.

To all whom it may concern:

Be it known that I, WALLACE ATHERTON McCURD, a subject of the King of Great Britain and Ireland, residing at "Bell-brook", Ballards Lane, North Finchley, in the county of Middlesex, England, have invented a new and useful Improvement in Flying-Machines, of which the following is a specification.

10 This invention relates to flying machines, and it consists in employing a series of planes which are caused to travel backward and forward in a suitable frame and to automatically reverse the angle of their inclination when their direction of travel is reversed.

15 In the accompanying drawing which shows by way of example one method of carrying this invention into practice:—Figure 1 is a view in side elevation, Fig. 2 is a view in end elevation, and Fig. 3 is a broken view in side elevation on an enlarged scale of one of the aeroplanes.

20 Throughout the views similar parts are marked with like letters of reference.

The frame *a* of the machine, which may be of any suitable shape and construction, carries a series of guides or runner bars *b* *b*—arranged one over the other and preferably 25 in parallel relation to one another. On these guides are mounted a series of planes *c* which planes are so mounted that they can be caused to travel backward and forward in the frame and so that their angle of inclination can be altered or reversed. One 30 method of attaining this end is that illustrated which consists in mounting each plane at or about the center of its length on a pair of brackets *d* which carry four rollers or pulleys *e*¹, *e*², *e*³ and *e*⁴. The two former are arranged one over the other and are 35 adapted to contact the upper and under sides of the guides or runner bars *b*, and the two latter (*e*³ and *e*⁴) are arranged fore and aft respectively of the other rollers, the said 40 rollers *e*³ and *e*⁴ when the plane is on an even keel being a short distance from the runner bars *b*. This distance may be made 45 capable of adjustment if desired to vary the 50 tilt of the plane. A downward extension of each bracket *d* forms an arm *f* by means of which the plane is caused to assume the desired angle, and through which the driving motion is imparted to it. Motion is imparted to the planes in any suitable manner, a convenient one being that illustrated

which consists of flexible cords *h* connected to the arms *f* and guided by suitable pulleys *j* carried by the frame *a*, motion being imparted to the said cords from any suitable 60 source of power, the arrangement being such that while one plane is traveling in one direction it is also imparting motion to another either in the same or in the opposite direction.

65 I do not limit myself to the use of any particular method of obtaining the necessary motion for imparting motion to the planes, that shown in the drawing being merely by way of illustration. It consists of a motor *l* driving a shaft *m* which carries a crank *m*¹ which is coupled by means of a connecting rod *n* to an oscillating frame *o* which imparts a reversing rotary motion to a pulley *p* to which the flexible cords *h* are attached.

70 It will be seen that the pull of the cords *h* first tilts the planes to the predetermined angle and then imparts motion to them, the angle of inclination and the direction of rotation being simultaneously altered.

75 It will be understood that any desired number of planes may be employed and that one half of them are caused to traverse the frame in one direction while the other half travels in the opposite direction.

80 What I claim as my invention, and desire to secure by Letters Patent, is:—

1. In a flying machine, a plurality of guides arranged one over the other, a plurality of planes adapted to traverse said guides and set at a predetermined angle to said guides, the inclination of one half of the planes being opposed to that of the other half, and means for imparting a reciprocating motion to said planes and for reversing 90 their angle of inclination, as and for the purpose set forth.

95 2. In a flying machine, a plurality of guides arranged one over the other and in parallel relation to one another, a plurality of planes adapted to traverse said guides and set at a predetermined angle to said guides, the inclination of one half of the planes being opposed to that of the other half, and means for imparting a reciprocating motion 100 to said planes and for automatically reversing their angle of inclination as and when their direction is reversed, as and for the purpose set forth.

105 3. In a flying machine, a plurality of guides arranged one over the other and in parallel relation to one another, a plurality,

of planes adapted to traverse said guides in pairs in opposite directions said planes being set at a predetermined angle to said guides, the inclination of one of each pair of planes being opposed to that of the other, and means for imparting a reciprocating motion to said planes and for reversing their angle of inclination as and when their direction is reversed, as and for the purpose set forth.

4. In a flying machine, a plurality of guides arranged one over the other and in parallel relation to one another, a plurality of planes set at a predetermined angle to

said guides and mounted to traverse said guides one half of said planes moving in a direction opposite to that of the other half and the inclination of one half of the planes being opposed to that of the other half, means for imparting reciprocating motion to said planes, and means for automatically reversing the angle of inclination of said planes as and for the purpose set forth.

WALLACE AERTHON McCURD.
